KEY RETAINER

Louis Schumer, Brooklyn, N. Y.

Application March 17, 1953, Serial No. 342,913

5 Claims. (Cl. 70—456)

This invention is directed to a new simplified and serviceable key retainer and its dominant objects, salient features and functional and structural advantages will appear from the following detailed specification taken with the accompanying drawings wherein:

Fig. 1 is a front elevational view of the key retainer according to my invention.

Fig. 2 is a side view of Fig. 1 illustrating the slidable bar closed and locked to preclude removal of the key hangers.

Fig. 2A is a view similar to Fig. 2, however showing the bar or shutter raised to permit removal or insertion of the key hangers.

Fig. 3 is a plan view of Fig. 1.

Fig. 3A is a sectional view on the line 3A—3A of Fig. 1.

Fig. 3B is a bottom view of the key retainer on a smaller scale and taken on the line 3B—3B of Fig. 1.

Fig. 4 is a rear view of Fig. 1, illustrating the shutter bar closed and locked.

Fig. 5 is a transverse sectional view on the line 5—5 of Fig. 4.

Fig. 6 is a view similar to Fig. 4 but showing the shutter bar raised, and

Fig. 7 is a transverse sectional view on the line 7—7 of Fig. 6.

Illustrative of the embodiment disclosed, the key retainer is generally indicated KR and comprises the rectilinear plate 10 provided with spaced depending hollow and arcuate beads 11, spaced apart by slots 12.

Heads 13 of key hangers H are removably supported by a pair of arcuate beads 11. Heads 13 are wider than slots 12 although shanks S carrying these heads may be threaded therein as is well appreciated.

The spaced beads 11 at the rear thereof form vertical gaps G adapted to be opened or closed by the shutter bar SB which extends across the entire length of the posterior or rear face of rectilinear plate 10.

Extending forwardly of bar SB and at the ends thereof and substantially normal thereto are the spaced ears E which closely and slidably embrace or straddle the end beads of plate 10. Bar SB also embodies turned-in lips L defining guide channels C (Fig. 3A) to permit linear movement of bar SB towards and closely aside of free terminals T of beads 11. In such relation bar SB covers gaps G to keep the hangers in beads 11 and thus preclude their removal. To keep the bar closed and locked, plate 10 embodies the struck out detent or projection D cooperating with the upper margin of bar SB to preclude upward displacement of bar SB away from terminals T (Fig. 5). However this bar is slightly curved, having its inner surface concaved and its outer surface convex as shown to provide ample clearance to permit bar SB to ride on projection D when this bar is deliberately urged upward by finger pressure against ears E. Projection D also frictionally cooperates with arcuate bar SB to hold the latter raised or fully open (Fig. 7) to permit removal or insertion of the hangers

2

out of or into beaded portion of plate 10. In fact projection D may be considered as a lock cooperating to hold bar SB shut and a frictional lock to hold the bar open.

5 It should be observed that the spaced lips L in fact constitute keepers movably straddling the ends of plate 10 and movably retain shutter bar SB on this plate.

To operate bar SB, ears E are grasped between a finger and thumb of the operator and are urged towards 10 or away from the bottom part of plate 10, that is, the beaded part. If urged upwardly, the bar is slidably shifted upward against the resistance offered by projection D to open the plate to permit prompt access to the spaced and free terminals T to suspend or remove key hangers. Spaced stops ST limit such upward movement. These stops are constituted by the lower parts of flange F integral with and extending rearwardly of plate 10. To close the key retainer, shutter or closure bar SB is urged downwardly by manipulating ears E to snap by 20 detent D which locks the bar in its closed relation against accidental opening.

Various changes may be made in details of construction and arrangement of parts without departing from the spirit of the invention or sacrificing any of the advantages thereof inherent therein.

I claim:

1. A key retainer adapted to removably support key hangers, comprising; a plate embodying spaced beaded portions defining spaced slots to removably receive said hangers and defining rearwardly extending free terminals for sustaining said hangers, said terminals being spaced apart from the body of said plate to define spaced gaps in communication with said slots, a bar movable towards or away from said terminals and disposed at the rear of said plate for removably closing said gaps and for removably bridging said slots, said bar having guide means cooperating with said plate to permit linear movement of said bar towards or away from said gaps and terminals, and detent means integral with and extending at the rear of said plate for cooperating with said bar to removably hold the latter against said terminals to removably close said gaps.

2. A key retainer adapted to removably support key hangers, comprising; a plate embodying spaced beaded portions defining spaced slots to removably receive said hangers and defining rearwardly extending free terminals for sustaining said hangers, said terminals being spaced apart from the body of said plate to define spaced gaps in communication with said slots, a bar movable towards or away from said terminals and disposed longitudinally of and at the rear of said plate for removably closing said gaps and for removably bridging said slots, said bar having guide means cooperating with said plate to permit linear movement of said bar towards or away from said gaps and terminals, and detent means integral with and extending from and rearwardly of said plate to frictionally cooperate with said bar to hold the latter away from said terminals to permit uninterrupted access to said gaps and terminals.

3. A key retainer adapted to removably support key hangers, comprising; a plate embodying spaced beaded portions defining spaced slots to removably receive said hangers and defining rearwardly extending free terminals for sustaining said hangers, said terminals being spaced apart from the body of said plate to define spaced gaps in communication with said slots, a bar movable towards or away from said terminals and disposed longitudinally of and at the rear of said plate for removably closing said gaps and for removably bridging said slots, said bar having terminal guide means cooperating with said plate to permit linear movement of said bar towards or away from said gaps and terminals, detent means in-

tegral with and extending from and rearwardly and substantially medially of said plate to cooperate with said bar to removably hold the latter against said terminals to removably close said gaps, and stop means carried by said plate and cooperating with said bar to limit displacement of said bar away from said terminals.

4. A key retainer adapted to removably support key hangers, comprising; a plate embodying spaced beaded portions defining spaced slots to removably receive said hangers and defining rearwardly extending free terminals for sustaining said hangers, said terminals being spaced apart from the body of said plate to define spaced gaps in communication with said slots, a bar having an exteriorly convexed and an internally concaved face and movable towards or away from said terminals and disposed longitudinally of and at the rear of said plate for removably closing said gaps and for removably bridging said slots, said bar having terminal guide means cooperating with spaced marginal portions of said plate to permit linear movement of said bar towards or away from said gaps and terminals, and a detent integral with and extending from and rearwardly of said plate to cooperate with a medial portion of said bar to removably hold the latter against said terminals to removably close said gaps and to frictionally cooperate with said concaved face to hold said bar away from said terminals and gaps.

5. A key retainer adapted to removably support key

hangers, comprising; a plate embodying a plurality of aligned spaced beaded portions defining spaced slots to removably receive said hangers and defining rearwardly extending free terminals for sustaining said hangers, said terminals being spaced apart from the body of said plate to define spaced gaps in communication with said slots, an exteriorly convexed and internally concaved bar movable towards or away from said terminals and disposed at the rear of said plate for removably closing said gaps and for removably bridging said slots, said bar having guide means cooperating with said plate to permit linear movement of said bar towards or away from said gaps and terminals, a detent integral with and extending from and rearwardly of said plate to cooperate with a medial portion of said bar to removably hold the latter against said terminals to removably close said gaps, and ears extending from said bar for removably straddling the end beaded portions of said plurality.
